UNITED STATES PATENT OFFICE.

GILBERT W. GOODRIDGE, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ELECTRIC SWITCH.

1,235,157.

Specification of Letters Patent. Patented Feb. 5, 1918.

Application filed November 6, 1916. Serial No. 129,794.

To all whom it may concern:

Be it known that I, GILBERT W. GOODRIDGE, a citizen of the United States of America, and residing at Bridgeport, in the county of Fairfield and State of Connecticut, have invented a certain new and useful Improvement in Electric Switches, of which the following is a specification.

My invention relates to electric switches and particularly to switches of the push button type, the object of my invention being to provide means for cushioning the operation of the switch mechanism so as to lessen the noise usually incident to its operation.

In the accompanying drawings.

Figure 1 is a plan partly in section on the line 1—1, Fig. 2 of a switch in which my invention is embodied in one form:

Fig. 2 is a longitudinal section therethrough:

Fig. 3 is a perspective of the switch frame;

Fig. 4 is a plan view thereof:

Fig. 5 is a section through the switch bar; and

Fig. 6 is a perspective view of the latter.

The switch mechanism here shown is of the general type illustrated in the co-pending application of Carl Eric Anderson, Serial No. 127,146, but it is to be understood that the improvements to which my invention relates may be applied to various other constructions and is not limited to the particular mechanism illustrated. As here shown, however, the switch comprises the usual insulating body 10 of cup shape providing an interior switch chamber within which are mounted the switch terminals 11 carried by the wire terminals 12 to which the wire connections are led through openings 13 formed in the upper corners of the body 10. A cover plate 14 overlies the switch chamber and is carried by a yoke 15 which in turn is held in position on the body 10 by the screw bolts 16.

The switch mechanism is mounted within the chamber on a frame comprising a base 17 with offset ends 18 tapped at 19 to receive the securing screws 20. Standards 21 rise from opposite sides of the base and support the rocker 22 and switch bar 23 carrying the blades 24 all mounted and arranged in the manner described in the application

above referred to. An operative connection 55 between the rocker 22 and the switch bar 23 is established through the switch spring 25, one end of which abuts against the cross pin 26 which extends between the plates comprising the rocker 22, while the other end 60 bears against the bridge 27 of the switch bar. The parts are so positioned with relation to each other that, upon the oscillation of the rocker 22 by means of the push buttons 28 and 29, the end of the spring 25 bearing 65 against the rocker is shifted from one side to the other of the axis of oscillation 70 of the switch bar and thus effects the throw of the switch bar from "off" to "on" position, or vice versa, with a snap action 75.

As explained in the application above mentioned the lugs 31 of the rocker 22 are halted at the extremes of their stroke by their impingement against the base 17 of the frame. In like manner the throw of 75 the switch bar 23 is limited by its impingement against the stops 32 and 33 formed at the free ends of the standards 21. Under the action of the switch spring 25 the throw of the rocker 22 and the switch bar 23 is 80 sharp and the resulting impact of these parts against their stops causes a more or less noisy operation of the switch. I have found that this may be to a large extent eliminated by cushioning the impact of both 85 rocker and switch bar, and particularly that of the switch bar. While this may be accomplished in various ways, a simple arrangement for this purpose is illustrated. Thus for the switch bar I have utilized a 90 light plate of spring sheet metal 34, riveted at 35 to the inner face of the bridge 27 of the switch bar and provided with wings 36 and 37 extending on opposite sides of the bridge piece and spaced therefrom, as best 95 illustrated in Fig. 5. A central aperture 38 is also provided in register with the aperture 39 in the bridge piece to accommodate the head of the guide pin 40 for the switch spring. Upon the throw of the switch bar 100 from stop lugs 33 to stop lugs 32 the shock of impact which is normally taken directly by the bridge of switch bar 27 is now taken by the spring wing 36; while on the throw 105 of the switch bar in the opposite direction its impact against the stops 33 is taken by the spring wing 37.

In like manner I rivet at 41 to the base 17

of the frame a spring plate 42, the ends 43 and 44 of which are angled slightly upward out of contact with the base. Upon the throw of the rocker 22 in one direction or the other its lugs 31 impinge not against the rigid base 17 as heretofore, but against the raised ends 43 or 44 of the spring plate 42 which thus cushion the impact of the rocker against the base.

10 The provision of these cushioning springs involves no material increase in the cost of manufacture of the switch, since the spring metal of which they are made is quite inexpensive and the parts are readily shaped by stamping, while their attachment to the frame and switch bar respectively is quickly accomplished by means of a simple riveting operation.

15 The operation of the switch is in no way affected save that it is silenced and the mechanism as a whole relieved from the detrimental effects incident to the hard shock of impact which heretofore has been incidental to the snap action of the mechanism 20 of switches of this general type. As above stated the invention is not limited to the particular mechanism shown nor is it limited to the precise form of cushioning springs employed, which may be variously 25 modified both in construction and arrangement without departing from what I claim as my invention.

I claim as my invention:—

1. A switch mechanism comprising an oscillating switch bar having a bridge piece, 35 abutments against which the opposite sides of said bridge piece impinge to limit the throw of the switch bar, in combination with a plate secured to the face of said bridge piece and having spring wings overlying the opposite sides of said bridge piece and spaced therefrom to cushion the impact of the switch bar against said abutments.

2. A switch mechanism comprising an oscillating switch bar having a bridge piece, 45 abutments against which the opposite sides of said bridge piece impinge to limit the throw of the switch bar, in combination with a plate secured to the face of said bridge piece and having spring wings overlying the opposite sides of said bridge piece and spaced therefrom to cushion the impact of the switch bar against said abutments, together with a switch spring and 50 a guide therefor piercing said spring plate and bridge piece.

In testimony whereof I have signed my name to this specification, in the presence of two subscribing witnesses.

GILBERT W. GOODRIDGE.
